COMBINATION CURTAIN, DRAPERY, AND SHADE FIXTURE

Neil Chatterton, Oswego, N. Y., assignor to The Neil Chatterton Associates, Oswego, N. Y., a copartnership

Application October 18, 1946, Serial No. 704,240

6 Claims. (Cl. 248—252)

1

The present invention relates to fixtures for supporting curtains, draperies and window shades, and more especially to a new and improved combination fixture having for its primary objects simplicity of form and construction, low cost of manufacture, and flexibility of adjustment to conform to a wide range of conditions most commonly encountered in use.

A further object of the invention is to provide a fixture of the foregoing character which may be quickly and easily installed and anchored to the face of a window frame, and which permits both the curtains and draperies to be adjusted relative to the shade, as well as independent adjustment of the same relative to the window and/or the floor, all without change of the fixture anchoring means and consequent marring of the window frame.

In attaining the aforementioned objectives, my invention is characterized by the provision of a slotted anchor plate or base which may be permanently installed, in pairs, on the window frame, with one anchor plate at one side of the frame and the other anchor plate at the opposite side of the frame, preferably at or near the junction of the vertical face boards and the head board. Each anchor plate or base is so constructed as to permit a window shade bracket and a separate multi-way curtain or drapery rod supporting bracket to be connected directly thereto, or alternatively, to supporting bars or arms having provision for vertically and horizontally adjusting the brackets thereon, and which are in turn connected to the anchor plate for selective adjustment as a whole in a vertical plane. In the case of the window shade brackets, provision is also preferably made for adjusting the same laterally to compensate for minor variations in the lengths of different window shade rollers.

Other important characteristics of my invention are rigidity and exceptionally great strength of the fixture assembly in all positions of adjustment, and the ease and facility with which the adjustments may be made, particularly in adapting the same to different types of curtain or drapery supporting rods, as permitted by the multi-way bracket aforesaid, and in adjusting the height and lateral spacing of the curtains and drapes, or their distance from the floor, without the aid of a tape measure or other measuring instrumentalities.

Other and further objects and advantages of the invention will be hereinafter described and

2

the novel features thereof defined by the appended claims.

In the drawings;

Figure 1 is a fragmentary view in front elevation, showing the upper portion of a window frame with a pair of my new combination curtain, drapery and window shade fixtures applied thereto;

Figure 2 is a top plan view of the arrangement shown in Figure 1;

Figure 3 is a vertical sectional view taken on the line 3—3 of Figure 1, on an enlarged scale;

Figure 4 is a fragmentary view in front elevation, showing a modified arrangement of one of the fixtures, with the multi-way bracket and window shade bracket both mounted directly on the anchor plate or base, and eliminating the adjustable supporting bars or arms which are shown in the arrangement depicted in Figure 1;

Figure 5 is a horizontal sectional view taken on the line 5—5 of Figure 4;

Figure 6 is a view in elevation of the multi-way curtain and drapery rod supporting bracket per se; and

Figure 7 is a perspective view of the window shade supporting bracket per se.

Like reference characters designate corresponding parts in the several figures of the drawings, wherein 1, 1 generally denote in their entireties a pair of fixtures constructed in accordance with my invention, as adapted for the support of curtains, draperies and a window shade, with the fixtures anchored to the face of a window frame, generally designated 2, at the respective opposite sides thereof near the top of the window frame. The fixtures are of substantially identical construction, and the component parts thereof are preferably made of metal or other suitable material having sufficient strength and rigidity.

As best shown in Figures 1 to 3 inclusive, each fixture includes an elongated anchor plate or base, designated 3, the opposite ends of which are offset rearwardly and provided with openings extending therethrough to receive suitable fastenings, such as screws 4. In installing the anchor plates on the window frame 2, they are preferably mounted flush with the inner edges of the vertical face boards 5 of the window frame, with the upper extremity of the anchor plate located at or near the junction of the vertical face boards 5 with the head board 6. However, if desired, the anchor plates may be secured to any convenient part of the window frame, al-

though the preferred location referred to above has the advantage of uniformity of location without resort to measuring instrumentalities, and the further advantage of affording the maximum range of adjustment of the curtain and drapery rod supports and the window shade bracket as will be hereinafter more fully described.

Each anchor plate 3 is longitudinally slotted, as at 7, with the opposite extremities of the slot continued partly along the offset portions of the anchor plate and terminating at the extreme ends of the slot in enlarged openings of generally semi-circular outline, as indicated at 8, 8, for the reception of a headed screw fastening 9. The screw fastening 9 is preferably provided with a shank of square or rectangular cross-section of such size as to be freely slideable in the slot 7 after the head 10 has been entered in one of the enlarged openings 8 at the end of the slot, and when the screw fastening is disposed in the slot, it is prevented from turning on its own axis. The shank of the screw fastening is threaded for engagement with a nut 11, the periphery of which is preferably knurled to facilitate tightening of the nut. To further aid in tightening the nut 11, the nut is preferably provided with a transversely or diametrically extended slot 12 in the outer face thereof to receive a screwdriver, coin, or other mechanical instrumentality such as is commonly available in a household.

At the opposite ends of the slot 7 in each anchor plate, and disposed in a plane behind the intermediate portion of the anchor plate which is spaced forwardly from the face of the window frame when the anchor plate is mounted on the window frame, the slot is widened as at 13, 13 to receive a flat bar or arm 14. When the arm or bar 14 is passed through the widened ends 13, 13 of the slot in the anchor plate, the arm or bar will lie in a vertical position, spaced slightly forwardly from the face of the window frame, with the arm or bar slidably engaging the inner face of the intermediate portion of the anchor plate, as best shown in Figure 3 of the drawings. The vertical arm or bar 14 is preferably provided with a series of spaced keyhole slots 15 to receive the headed fastening 9 which serves to rigidly secure the bar or arm to the anchor plate 3. In making the connection between the bar or arm 14 and the anchor plate 3, the headed fastening 9 may first be inserted in one of the keyhole slots 15, following which the bar or arm 14 may be inserted through the anchor plate from top to bottom or from bottom to top, until the headed fastening is disposed in the slot 7 of the anchor plate. Thereupon, the nut 11 may be tightened to firmly secure the arm or bar 14 to the anchor plate 3. A substantial range of vertical adjustment of the bar or arm 14 may be attained by the selective engagement of the headed fastening 9 in any one of the keyhole slots 15, in addition to which the slot 7 in the anchor plate 3 affords a further range of vertical adjustment of the bar or arm with the headed fastening 9 engaged in any given keyhole slot.

A second bar or arm 16 is preferably provided for attachment to the vertical bar or arm 14 in a horizontal position, said second bar or arm 16 being a duplicate of the bar or arm 14. The bar or arm 16 is also provided with a series of spaced keyhole or bayonet slots 17 for receiving a second headed fastening 18 which is preferably identical with the headed fastening 9, being provided with a square threaded shank so as to

5 prevent turning of the fastening when it is moved into the narrow portions of the respective keyhole or bayonet slots 15 and 17. In mounting the horizontal bar or arm 16 on the vertical bar or arm 14, the headed fastening 18 may first be passed through a selected one of the slots 17 and a nut loosely applied onto the shank of the fastening. Thereafter, the head of the fastening may be passed through the enlarged portion of one of the keyhole slots 15 of the bar 14, and the nut finally tightened up so as to rigidly secure the two bars together and prevent them from moving relative to each other.

6 Each fixture includes a multi-way curtain and drapery rod supporting bracket generally designated 19, said bracket including a bifurcated arm 20 for receiving thereon a conventional type of curtain or drapery supporting rod, a second hook-shaped arm 21 extending from the bracket 20 in a plane at right angles to the arm 20, and a third arm 22 extending from the bracket in still another plane, and terminating in a cylindrical collar 23. The arms 21 and 22 are so designed as to engage with still other conventional types of curtain and drapery supporting rods such as are commonly in use. For the purpose of mounting the curtain and drapery support bracket 19, the bracket is provided with two openings of 25 rectangular configuration respectively designated 24 and 25, the opening 24 being located at the intersection of the two arms 22 and 20, and the opening 25 being located in the arm 21. These openings are adapted to selectively receive therein a headed fastening 26 identical with the 30 fastenings 9 and 18, so that the bracket 19 may be mounted in either of two major positions, in each of which the bracket may be shifted about the axis of the fastening 26 to selectively dispose the respective arms in operative position 35 for engaging different types of curtain and drapery supporting rods (not shown). In Figures 1 to 3 of the drawings, the bracket 19 is shown mounted on the horizontal arm or bar 16, with the fastening 26 selectively engaged in one 40 of the keyhole slots 17. It will be obvious that the bracket 19 may be horizontally adjusted along the arm 16 by suitably engaging the fastening 26 in any other selected slot 17, or, if preferred, the arm 16 may be dispensed with entirely, and the bracket 19 mounted directly on the vertical arm or bar 14, by suitably engaging the fastening 26 in one of the slots 15. In the latter case, the bracket 19 can be adjusted in a 45 vertical direction only, although, of course, the bracket is shiftable about the axis of the fastening 26 to various positions that will present the respective bracket arms for use in engaging the particular type of curtain or drapery supporting rod which is to be employed in hanging the 50 curtains and drapes.

55 A still further modified arrangement of the bracket 19 is shown in Figures 4 and 5 of the drawings, wherein the bracket is mounted directly on the anchor plate or base 3, and both of the 60 bars or arms 14 and 16 are dispensed with entirely. In the arrangement shown in Figures 4 and 5, it will be understood that the bracket 19 is adjustable vertically to a limited extent by suitably sliding the fastening along the slot 7 between the extreme limits of the slot, and in addition, the bracket may be shifted to different positions about the axis of the fastening, and the fastening can be engaged in either of the two 65 openings 24 or 25, as desired.

70 In addition to the bracket 19, each fixture also

includes a second bracket generally designated 27, the latter serving to support a window shade. The bracket 27 is preferably L-shaped, and includes two arms respectively designated 28 and 29, the former being slotted, as indicated at 30, and serving to receive therein the headed fastening 9, as illustrated in Figures 1 to 5 inclusive, and being vertically adjustable relative to the anchor plate or base 3, as well as laterally adjustable relative to the inner edge of the window frame, as permitted by the elongation of the slot 30. The arm 29 of the bracket 27 is suitably apertured to engage one end of a conventional window shade roller, such rollers usually being provided with a circular pin at one end and a rectangular pin at the other end. Accordingly, the brackets 27 are so constructed as to be righthand or lefthand when applied in pairs to a given window, one of said brackets preferably having two circular openings 31 in the arm 29 thereof, and the other bracket being provided with a pair of rectangular openings 32 in the arm 29. By providing a pair of such openings in each bracket, the window shade may be mounted in either set of corresponding openings so as to allow for adjustment of the window shade towards and away from the window, or, in the alternative, two separate shades may be mounted on each window. A still further range of adjustment of the window shade towards and away from the window is provided by reversing the arms 29 of the respective brackets 27 so as to extend rearwardly towards the window, as illustrated in the drawings, or forwardly away from the window as in the case where the brackets are reversed or inverted when attached to the base plate or anchor plate 3. A still more refined adjustment of the brackets 27 towards and away from the window may be accomplished by seating the arm 28 on either the outer face of the anchor plate 3, or against the inner face of the anchor plate, or even against the inner face of the vertical arm or bar 14. If desired, more than one set of window shade supporting brackets 27 may be employed in a given installation. Instead of mounting the brackets 27 on the anchor plates 3, they may be selectively mounted in different positions on either the vertical bar 14 or the horizontal bar 16, or these brackets may be employed independently of either of these bars, or in combination therewith.

It will be understood from the foregoing that in the use of my new fixture, the anchor plates or bases 3 may be permanently installed on the window frame, and once installed, it becomes unnecessary to change the position of the same for the purpose of varying the vertical and horizontal adjustments of the brackets, thus completely eliminating undue marring of the window frame, and unsightly patches which are commonly made in the home when the conventional fixtures are changed from time to time. At the same time, my new fixture is extremely flexible in its adaptations to various conditions, and the brackets are not only adjustable so as to permit the upward adjustment of curtains or drapes that are too long, but also a downward adjustment can be effected to compensate for shrinkage of the curtains or drapes, and to enable the same to be hung at the proper distance from the floor. In the arrangement as illustrated in Figures 1 to 3 inclusive, the brackets 19 are adjustable both vertically and horizontally independently of the brackets 27, while in the arrangement as illustrated in Figures 4 and 5, both brackets may

be adjusted vertically simultaneously, while the bracket 27 is adjustable laterally as well. The adjustments can be easily and quickly made without the exercise of any special skill, and when the desired position of the respective brackets is attained, they may be firmly secured in such positions by the simple expedient of tightening one or more screw fastenings. The component parts of the fixture are preferably made of cold-rolled steel, with substantially all surfaces of the parts made flat so as to facilitate adjustment thereof and secure fastening of the parts in adjusted position.

While the specific details have been herein shown and described, the invention is not confined thereto as changes and alterations may be made without departing from the spirit thereof as defined in the appended claims.

I claim:

1. A fixture of the class described, comprising an anchor plate having an elongated slot formed therein and terminating at each of its opposite ends in a rearwardly offset enlarged opening for the reception of the head of a headed screw fastening, the body of the screw fastening being free to slide in the slot aforesaid and being flattened on at least two sides to prevent rotation of the screw fastening when disposed in the slot, a bracket having an opening therethrough for receiving the body of the screw fastening, a nut threadedly engaging the body of the screw fastening for clamping the bracket to the anchor plate in selective positions of adjustment lengthwise of the slot, a bar slidably mounted in the anchor plate and having a plurality of longitudinally spaced openings therein selectively registerable with the slot in the anchor plate for receiving the screw fastening, a second bar having a plurality of corresponding longitudinally spaced openings, each of which is selectively registerable with the openings in the first bar, with the second bar disposed transversely of the first bar, a screw fastening engageable through the registered openings of the bars for securing the same together, a second bracket, and another screw fastening selectively engageable with the openings in either bar for attaching the latter bracket thereto.
2. A combination curtain, drapery and window shade fixture, comprising an anchor plate having provision for attaching the same to a window frame, a window shade supporting bracket connected to the anchor plate for adjustable movements both vertically and horizontally, a second bracket having the form of a multi-way curtain and drapery rod support, and means for connecting said second bracket to the anchor plate in selective positions of adjustment, said last-mentioned connecting means including a pair of supporting bars each having a series of keyhole slots therein for selective registration one with the other, screw fastening means engageable in said slots for connecting the bars together with one bar disposed vertically and the other bar horizontally, additional screw fastening means selectively engageable with the slots in either bar for attaching the second bracket thereto, and means for attaching the vertical bar to the anchor plate.
3. A combination curtain, drapery and window shade fixture, comprising an anchor plate having provision for attaching the same to a window frame, a window shade supporting bracket connected to the anchor plate for adjustable movements both vertically and horizontally, a second

bracket having the form of a multi-way curtain and drapery rod support, and means for connecting said second bracket to the anchor plate in selective positions of adjustment, said last-mentioned connecting means including a pair of supporting bars each having a series of keyhole slots therein for selective registration one with the other, screw fastening means engageable in said slots for connecting the bars together with one bar disposed vertically and the other bar horizontally, additional screw fastening means selectively engageable with the slots in either bar for attaching the second bracket thereto, and means for adjustably attaching the vertical bar to the anchor plate for vertical adjustment of both bars and the second bracket as a whole and independently of adjustment of the bars and the second bracket relative to each other.

4. In a combination curtain, drapery and window shade fixture, a longitudinally slotted anchor plate having its opposite ends rearwardly offset and provided with openings to receive anchor fastenings for attaching the same to the face of a window frame, the rearwardly offset ends of said anchor plate being laterally slotted, an elongated flat bar slidable through the lateral slots aforesaid and lying behind the longitudinally slotted portion of the anchor plate between the offset ends of the latter, said bar being longer than the anchor plate and having a plurality of keyhole slots therein arranged at spaced intervals along the bar and selectively registrable with the longitudinal slot in the anchor plate, a headed screw fastening selectively engageable in the keyhole slots aforesaid and freely engageable in and removable from the anchor plate slot, said screw fastening being slidably adjustable in the anchor plate slot and serving to permit a limited longitudinal adjustment of the bar relative to the anchor plate when the screw fastening is engaged with a selected keyhole slot in the bar, a window shade supporting bracket adjustably mounted on the anchor plate and connected thereto by the screw fastening aforesaid, and a multi-way curtain and drapery rod supporting bracket adjustably mounted on the bar.

5. In a combination curtain, drapery and window shade fixture, a longitudinally slotted anchor plate having its opposite ends rearwardly offset and provided with openings to receive anchor fastenings for attaching the same to the face of a window frame, the rearwardly offset ends of said anchor plate being laterally slotted, an elongated flat bar slidable through the lateral slots aforesaid and lying behind the longitudinally slotted portion of the anchor plate between the offset ends of the latter, said bar being longer than the anchor plate and having a plurality of keyhole slots therein arranged at spaced intervals along the bar and selectively registrable with the longitudinal slot in the anchor plate, a headed screw fastening selectively engageable in the keyhole slots aforesaid and freely engageable in and

removable from the anchor plate slot, said screw fastening being slidably adjustable in the anchor plate slot and serving to permit a limited longitudinal adjustment of the bar relative to the anchor plate when the screw fastening is engaged with a selected keyhole slot in the bar, a window shade supporting bracket adjustably mounted on the anchor plate and connected thereto by the screw fastening aforesaid, and a multi-way curtain and drapery rod supporting bracket selectively attachable directly to the bar and the anchor plate respectively.

6. In a combination curtain, drapery and window shade fixture, a longitudinally slotted anchor plate having its opposite ends rearwardly offset and provided with openings to receive anchor fastenings for attaching the same to the face of a window frame, the rearwardly offset ends of said anchor plate being laterally slotted, an elongated flat bar slidable through the lateral slots aforesaid and lying behind the longitudinally slotted portion of the anchor plate between the offset ends of the latter, said bar being longer than the anchor plate and having a plurality of keyhole slots therein arranged at spaced intervals along the bar and selectively registrable with the longitudinal slot in the anchor plate, a headed screw fastening selectively engageable in the keyhole slots aforesaid and freely engageable in and removable from the anchor plate slot, said screw fastening being slidably adjustable in the anchor plate slot and serving to permit a limited longitudinal adjustment of the bar relative to the anchor plate when the screw fastening is engaged with a selected keyhole slot in the bar, a window shade supporting bracket adjustably mounted on the anchor plate and connected thereto by the screw fastening aforesaid, and a multi-way curtain and drapery rod supporting bracket selectively attachable directly to the bar and the anchor plate respectively, said multi-way bracket having a plurality of openings therein selectively engageable with the screw fastening aforesaid when attached directly to the anchor plate, and selectively engageable with a corresponding screw fastening which is itself selectively engageable in the keyhole slots in the bar when attached directly to the bar.
